1 Claim. (Cl. 349—6)

(Granted under Title 35, U.S. Code (1952), sec. 266)

This invention relates to a method and apparatus for locating a naval ordnance device such as a torpedo, depth charge or the like, which has sunk to the bed of a body of water at the end of a practice or testing period.

This application is a division of my copending application, Serial No. 205,396, filed January 10, 1951, now abandoned.

Several devices have been heretofore employed to recover practice torpedoes which have sunk to the bottom at the end of a practice period, but they have not proved to be entirely satisfactory under all conditions of service.

One prior method employs a stream-lined float which is towed through the water by a hoisting cable attached to the aft end of the torpedo. Frequent failure in the use of this method is caused by twist-breaking of the hoisting cable during the practice run and the float produces a drag in the water which materially reduces the speed of the torpedo.

Another locating apparatus heretofore devised for a torpedo employs a float having a length of line attached to the torpedo which is initially enclosed within the hand-hole of the torpedo by a handhold cover. The cover is provided with a control surface which is constructed so that the kinetic pressure of the water on the control surface during the forward motion of the torpedo holds the cover in the closed position. When the torpedo comes to rest on the bottom at the end of the practice run, the kinetic pressure on the control surface is relieved and the cover flies open to allow the float to rise to the surface to mark the location of the torpedo to aid a diver in locating the torpedo on the bottom. Such a device has not proven to be entirely satisfactory in service because the cover opens if the torpedo speed is materially reduced and the line which connects the float to the torpedo becomes entangled with the propeller blades.

According to the present invention an ultrasonic transmitter is disposed within a torpedo handhole and operates to transmit intermittent sonic signals in the water to radiate outwardly in all directions from the torpedo as the torpedo rests on the bottom.

A recovery vessel carries a directional hydrophone submerged within the water and produces the maximum response to the transmitted signals from the torpedo when the hydrophone is pointed directly toward the transmitter. The vessel is then steered on a course in the direction indicated by the hydrophone.

This preliminary search is done with the hydrophone arranged in a horizontal or azimuth-searching position.

As soon as the course of the searching vessel is established the hydrophone is rotated through 90° to point the response area of the hydrophone toward the bed of the water. When the signal received reaches a maximum with the hydrophone pointed downwardly, the vessel is directly over the lost torpedo and an anchored marker buoy dropped to mark the location on the surface of the water.

The next step is for a diver to descend to the bottom adjacent the buoy to exactly locate the torpedo and secure a hoisting cable to the torpedo. The diver carries a portable directional hydrophone similar to the hydrophone carried by the vessel which is connected to the

2

earphones in the diving helmet to allow the diver to listen while he seeks the torpedo with his hydrophone.

One of the objects of the present invention is to provide a new and improved method and apparatus for locating a torpedo which has sunk to the bed of a body of water at the end of a practice or testing period.

Another object is to provide such a locating apparatus which will not interfere with the operation of the torpedo during the testing period.

10 Still another object is to provide a new and improved mechanism for broadcasting sonic signals from a torpedo in all directions into the surrounding water at the end of a practice or test run.

A still further object is to provide a sonic signal broadcasting mechanism which may be fitted into the hand-hole of a torpedo.

Other objects and many of the attendant advantages of this invention will be readily appreciated as the same becomes better understood by reference to the following detailed description when considered in connection with the accompanying drawings wherein:

FIG. 1 illustrates a diver employing a portable directional hydrophone for locating a practice torpedo which has sunk to the bottom;

25 FIG. 2 is a sectional view of the sound emitting mechanism which is fitted into the torpedo handhole prior to launching the torpedo on a practice run;

FIG. 3 is a transducer in section connected to the operating circuit employed in connection with the present invention for broadcasting sound signals from the torpedo into the surrounding water; and

30 FIG. 4 is the oscillating circuit, schematically illustrated, employed for energizing the transducer.

Referring now to the drawings on which like numerals 35 are employed to designate like parts throughout the several views and more particularly to FIG. 1, there is shown thereon a recovery vessel 10 from which a diver 11 has been lowered to seek a torpedo 12 which has sunk to the bottom at the end of a practice run. The diver 11 carries a portable directional hydrophone 13 connected electrically to earphones (not shown) enclosed within the helmet 14 of the diver. The portable hydrophone 13 is adapted to receive the maximum response when the flexible diaphragm 15 is pointed directly at the torpedo

40 12 which broadcasts radiating sound signals into the surrounding water. The sound signals broadcast from the torpedo 12, originate from a transmitter enclosed within a handhole 16.

45 As shown in FIG. 2 the signal transmitter, generally 50 designated 17, comprises a tubular casing 18 telescopingly arranged within the torpedo handhole 16. The bottom end of casing 18 is sealed in watertight relation by a pair of metallic disks 19 slidably arranged within the casing and having a rubber gasket 21 disposed therebetween which expands radially into watertight relation with respect to the casing as the disks are forced toward each other as nuts 22 are tightened on the spaced rods 23. The upper portion of casing 18 is provided with a radial flange 29 having suitable openings therethrough for receiving bolts 33 which engage the usual threaded recesses at the handhole opening.

55 An expandible gasket 30 disposed between the flange 29 and the handhole opening forms a watertight seal therebetween as the bolts 33 are tightened. A metallic cover 34, formed to follow the contour of the torpedo exercise head, is secured to the flange 29 by set screws 35.

60 The spacer rods 23 have secured to the mid-portion thereof a supporting disk 24 which separates the oscillator unit 25 from the power source comprising the A battery 26 and the B battery 27. Disk 24 is provided with suitable insulated openings therethrough for receiving connector pins 6, 7, and 8 respectively for electrically connecting the oscillator unit 25 to the batteries 26 and 27.

Tie rods 5, extend through suitable openings in spacer rods 23 and have secured to the upper end thereof disk 4 for securing batteries 26 and 27 to prevent endwise movement thereof within the casing 18. The batteries 26 and 27 are provided with a centrally disposed opening 36 containing the insulated contact rod 37 which terminates with a spring terminal 39 which connects the oscillator unit 25 and transducer unit 32. The transducer unit 32, operated by the oscillator 25, is acoustically coupled to the cover 34 and casing 18 and produces sound signals which are thus transmitted through the surrounding water in all directions from the torpedo as it rests on the bottom.

Referring now more particularly to FIG. 3 there is shown in section the transducer 32 suitable for the purpose comprising a non-magnetic housing 41 having a cylindrical end portion 42 closed in liquid-tight relation by a flexible cover 43, preferably rubber, which is secured to the end portion 42 in fluid tight relation by a pair of binding wires 44.

The housing 41 is provided with a threaded opening 45 containing an expandable gasket 46 disposed between a pair of washers 47. The gasket 46 seals the opening 45 as the non-magnetic pipe plug 48 forces the washers 47 toward each other as the plug is tightened in the opening 45. A conductor 51 is connected to a terminal 50 of an insulated rod 40 which is sealed in an opening through the pipe plug 48 and maintained in yieldable contact with spring terminal 39 thereof to form an electrical connection between the crystals 53 of transducer 32 and the oscillator unit 25. A second conductor 52, connected to alternate layers of foil 54, is grounded to housing 41 which, in turn, is grounded to the casing 18 when the transducer is assembled therein. The oscillator circuit may be of any well known pinging type which will preferably intermittently energize the transducer at 45 kc. Such an oscillator which is suitable for this purpose may be of the same general type as that disclosed in the copending application of Ford L. Johnson et al., Serial No. 657,310, filed March 26, 1946, for Distance Measuring Apparatus.

Disposed within the housing 41 are a pile of Rochelle salt crystals 53 with thin sheets of foil 54 separating the crystals from each other. The area between the crystals 53, casing 41 and cover 43 is entirely filled with castor oil. The crystals 53 are electrically connected to conductors 51 and 52 and are adapted to transform electrical pulses into pinging sonic pulses when operated by the oscillator circuit 25.

The pulsing oscillator circuit 25 is adapted to cause the crystal elements 53 to be driven intermittently at a pre-determined rate such, for example, as 45 kc., the oscillator being operated from the batteries 26 and 27, thereby causing vibrations which are transmitted through the water as sonic pulses radiating in all directions from the torpedo.

The recovery vessel 10 is provided with a searching device including a hydrophone which is mounted on the vessel. This hydrophone is used to bring the vessel directly over the lost torpedo at which point an anchored marker buoy is dropped from the vessel.

The next step is for the diver 11 carrying the portable hydrophone 13, to descend to the bottom adjacent the marker buoy. The hydrophone 13 is connected to suitable receivers and amplifiers (not shown) located on the search vessel and then to the earphones (not shown) enclosed within the helmet 14. The portable hydrophone will receive the maximum response from the transmitter 17 in the torpedo when the diaphragm 15 of the portable hydrophone is pointed directly at the torpedo. Thus the diver, by following the maximum response in his earphones is guided to the submerged torpedo where a hoisting cable from the recovery vessel 10 may be attached to the torpedo.

Referring now to FIG. 4, there is disclosed therein a preferred type of pulsing oscillator circuit 25 which produces a large power output to the transmitter 32 and

causes the generated signals to be transmitted over long distances in the order of two miles while consuming only a small amount of power from the B battery. The circuit provides pulses of short duration compared with the interval between pulses, the duration of each pulse and the interval therebetween being determined primarily by the time constants in the grid circuits. Stated in other words, the oscillator circuit generates oscillatory energy at predetermined spaced intervals of low duty cycle.

The oscillating circuit 25 comprises triode tubes 75 and 76, the plates of which are connected to the tuned circuit comprising condenser 77 and inductances 78 and 81 which principally determine the carrier frequency.

The plate 82 of tube 75 is coupled to the grid 83 of tube 76 by capacitor 84 and in like manner plate 85 and grid 86 are interconnected by capacitor 87, thereby providing the proper feedback for oscillation. The resistors 88 and 89 and capacitors 84 and 87 are of such value that blocking occurs due to grid rectification thereby cutting off the tubes for a fixed interval between each period of oscillation. Resistor 88 may be made variable as indicated, if desired, to control the repetition rate of the pulses. The oscillating voltage generated in the plate circuit of tube 75 appears across inductance 81 and a portion of inductance 78. A substantial portion of this voltage exists across inductance 81 which provides a coupling impedance to drive the transducer 32. In this manner it will be understood that a large portion of the oscillatory energy of the circuit is delivered to the transducer for transmission into the surrounding water.

The capacitance of the transducer 32 is dependent on temperature and to minimize this effect condenser 79 is shunted across the transducer.

It will of course be understood that a similar transmitter may be disposed within a mine, depth charge, or other similar ordnance devices, to aid in locating these devices which have sunk to the bottom at the end of a practice or test period.

Obviously many modifications and variations of the present invention are possible in the light of the above teachings. It is therefore to be understood that within the scope of the appended claim the invention may be practiced otherwise than as specifically described.

The invention described herein may be manufactured and used by or for the Government of the United States of America for governmental purposes without the payment of any royalties thereon or therefor.

I claim:

In a system of the character disclosed, means for intermittently transmitting sound signals from a sunken torpedo having a casing with a handhole therein comprising, in combination, a tubular housing mounted within the handhole, an oscillating device mounted at the base of said housing, a cover enclosing said housing and acoustically connected to the torpedo casing, a transducer unit 50 acoustically engaging said cover and adapted to transmit sound signals therethrough and through the casing when the transducer is operated, a battery having an opening therethrough and disposed within said housing between said transducer and said oscillating device, and a contact rod disposed within said battery opening and operatively connected to said oscillating device and said transducer whereby the transducer is operated from said oscillating device.
